UNITED STATES PATENT OFFICE.

ALESSANDRO CUCCURULLO, OF BRESCIA, ITALY.

FIREARM.

1,193,768.

Specification of Letters Patent. Patented Aug. 8, 1916.

Application filed December 27, 1915. Serial No. 68,908.

To all whom it may concern:

Be it known that I, ALESSANDRO CUCCURULLO, a subject of the King of Italy, residing at Brescia, Italy, have invented certain new and useful Improvements in Firearms, of which the following is a specification.

This invention relates to an improvement in automatic fire-arms of the type in which the breech frame and block recoil on the body of the fire-arm after firing, and has for its object an arrangement for connecting the breech block with the breech frame when the shot is being fired and releasing the same from said breech frame after firing.

According to this invention the breech block is connected to the breech frame by means of a projection mounted on a locking arm pivoted on the breech frame said locking arm being caused to be swung by suitable means when the breech frame and block are recoiling so as to release said breech block and frame from each other. Said means for causing the swinging of the locking arm may be in form of a slope provided on the body of the fire-arm, said slope being engaged by a tail of the locking arm when the breech block and frame are recoiling.

The annexed drawing shows by way of example an arrangement according to this invention, said arrangement being shown applied to an automatic pistol for purpose of illustration, it being understood that the present invention may be applied to any kind of fire-arms in which the breech block and frame recoil after firing.

In said drawing Figure 1 is a longitudinal section of the upper portion of a pistol having its parts in the ordinary position, Fig. 2 is the same section with the parts in the position they occupy after firing; Fig. 3 is a rear view of the breech frame and Fig. 4 is a detail view showing one of the cheeks of the pistol body.

As shown in said figures the body comprises two cheeks 1, encircled by a slide 2 in which is mounted to reciprocate the breech frame 3 provided with the breech block 4. Said breech block 4 is provided in its lower portion with a notch 5 registering with an opening 6 provided in the lower portion of the breech frame, said opening and notch being intended to be engaged by a tooth causing the breech frame and block to be solid with each other when this is required by the operation of the fire arm, that is when

the shot is being fired. According to this invention said tooth is mounted at the end of a swinging arm 8 pivoted by means of a pin 9 on lugs 9' carried by the breech frame, said arm 8 having a tail 10 opposite a slope 11 provided on the body 1. A spring 12 pushes the arm 8 in the position shown in Fig. 1, that is with its tooth 7 engaged in opening 6 and recess 5 so that said breech frame 3 and block 4 are solid with each other when the shot is being fired. After firing the breech frame 3 is caused to recoil in the known manner, and then the tail 10 of arm 8 engages the slope 11 of body 1 and thus causes the arm 8 to rotate so as to withdraw the tooth 7 from notch 5, the breech block 4 being thus released from breech frame 3 and free to effect its backward stroke in order to eject the fired case and then to carry a fresh cartridge in the barrel during its return stroke which is caused by springs (not shown).

When the breech frame has been restored in its ordinary position by spring 15, the locking arm 8 is carried in the position shown in Fig. 1 by spring 12, so that it is ready to engage the breech block in order to cause it to be solid with the breech frame.

In the pistol illustrated by way of example the firing pin 16 is cocked before firing by an arm 13 engaging an arm 14 pivoted to said firing pin, said arm 13 being controlled by trigger 17, arm 18 and pin 19 engaging an opening 20 of said arm 13; in this case the arm 8 is provided with a longitudinal slot 8' for allowing the end of arm 13 to reach arm 14.

According to this invention the body cheeks do not require to be provided with grooves for controlling the locking block as required in the known types so that their solidity is increased. Further the operation of the fire-arm is made more safe and it may be easily taken to pieces as the breech frame and block are independent from the body, the locking member being mounted on the breech frame.

It is to be understood that the locking arm 8 may be operated by any other means than the slope 11 and that this invention may be applied to any kind of automatic fire-arms provided with recoiling breech frame and block, the pistol illustrated being shown merely by way of example.

What I claim as my invention and desire

o secure by United States Letters Patent
s:—

In an automatic fire-arm having recoiling breech frame and block, a body, a breech frame reciprocating on the same, a breech lock reciprocating in the breech frame, an opening in the breech frame and a notch in the breech bolt said opening and notch being intended to register with each other in the ordinary position of said parts, a spring controlled arm pivoted to the breech frame, a projection at one end of said arm, said projection being capable of engaging said open-

ing and notch, a tail on the opposite end of said arm, and a slope on the body of the fire-arm, said slope coöperating with said tail for swinging said arm and withdrawing said projection from said notch when the breech frame recoils after firing.

In witness whereof I have signed this 20 specification in the presence of two witnesses.

ALESSANDRO CUCCURULLO.
